UNITED STATES PATENT OFFICE.

RICHARD WOLFSBERG AND SIDNEY C. SMITH, OF LOS ANGELES, CALIFORNIA.

CIRCUIT-BREAKER.

1,253,761.

Specification of Letters Patent. Patented Jan. 15, 1918.

Application filed April 4, 1917. Serial No. 159,846.

To all whom it may concern:

Be it known that we, RICHARD WOLFSBERG and SIDNEY C. SMITH, both citizens of the United States, residing at Los Angeles, in the county of Los Angeles and State of California, have invented a new and useful Circuit-Breaker, of which the following is a specification.

An object of this invention is to insure the safety from electric shock of the person operating the circuit breaker and changing the fuses of said circuit breaker.

Another object is to effect the foregoing by a simple and reliable construction.

Other objects and advantages will appear in the subjoined detail description.

The accompanying drawings illustrate the invention:

Figure 1 is a front elevation of a circuit breaker built in accordance with this invention, the parts being in the positions they occupy when the circuit breaker is open and the fuses are exposed to view.

Fig. 2 is a perspective view of the circuit breaker, the parts being shown in the circuit closing positions.

Fig. 3 is a side elevation, the case being in section on line indicated by x^s-x^s , Fig. 1.

Fig. 4 is an elevation corresponding to Fig. 3 excepting that the parts are in the circuit closing positions as in Fig. 2.

Fig. 5 is a plan section on line indicated by x^s-x^s , Fig. 4.

Fig. 6 is a sectional detail on line indicated by x^s-x^s , Fig. 1.

Fig. 7 is a perspective view of the shield and its operating member.

There is provided a housing of any suitable construction, in the drawings said housing being in the form of a rectangular case comprising a top 1, bottom 2, sides 3, 4, back 5 and front 6. The front 6 is detachable and for this purpose is of separate construction from the top, bottom and sides of the case and is fastened by screws 7 or equivalents to the sides and bottom of the case.

The front 6 comprises two sections, a lower stationary section 8 which is fixed in place by the screws 7 and an upper movable section forming a door 9 which is hinged or pivoted at 10 to the lower section 8 so that it may be swung outward at an angle to the section 8 as in Fig. 3.

The door 9 may be locked in closed position, and for this purpose the top 1 of the case is provided at its forward edge with a

forwardly projecting hasp 11 having a downwardly projecting shoulder 12 forming an abutment adapted to extend in front of the door when in closed position so as to hold said door closed. The hasp 11 is also provided with a perforation 13 through which a suitable lock 14 may be fastened to prevent too ready opening of the door. Owing to the hasp 11 being bendable, in an emergency said hasp when the lock 14 is in locking position, may be bent upward sufficiently to allow the door to be opened, without removing the lock.

When the door 9 is in open position as in Fig. 3 it may be locked in such position, and for this purpose the door 9 is provided with an arm 15 extending at an angle to the plane of said door and having a perforation 16 adapted, when the door is in the position shown in Fig. 3, to register with another perforation 17 in one of the sides 3 of the case. The lock 14 may be removed from the hasp 11 and may be inserted through the perforations 16 and 17, thus locking the door against closing.

Fastened to the door 9 is a base 18 constructed of suitable insulation material such, for instance, as slate or the like, said base being fastened to the door by screws 18' or equivalents.

Mounted on the base 18, and insulated thereby from the door 9 are fuse contacts 19, 20 and switch contacts 21, 22. The fuse contacts 19, 20 may be furcated so as to receive between the furcations thereof the terminal blades 23, 24 of fuses 25. Thus the fuses 25 may be readily detached and new ones installed in place thereof when replacement becomes desirable or necessary. The contacts 19, 21 are electrically connected together and the contacts 20, 22 are electrically connected together and for this purpose the contacts 19, 21 may be made integral with one another as may also the contacts 20, 22 as shown in the drawings.

When the door 9 is in closed position as in Fig. 4 the contacts 21 engage upper stationary contacts 26 which project downward from an insulation block 27 fastened on the inside of the top 1 of the case. Also when the door is in said closed position the contact 22 engages a lower stationary contact 28 mounted on an insulation member 29 which is suitably fastened to the bottom 2 of the case. Thus the contacts 26, 28 are insulated from the case and said contacts may be fur-

cated, if desired, and the contacts 21, 22 may be in the form of blades so as to be embraced by the furcations of the contacts 26, 28 in a manner well understood in the art.

- 5 When the door 9 is in open position as in Fig. 3 the inner end of the base 18 projects into the case to the rear of the hinge 10 to form a stop or abutment 30 which engages a shield 31 that may be in the form of a flat 10 plate and that is hinged or pivoted at 32 to the back 5 of the case. The hinge 10 as shown may be below the level of the hinge 32 so that when the door 9 is in open position with the plane of the shield 31 coinciding 15 with the plane of the door 9 said door 9 and shield 31 will extend aslant downwardly and forwardly. When the door and shield are in this position the space *a* inside of the case beneath the shield 31 is inaccessible, the 20 shield 31 absolutely preventing the operator of the device from getting his hands or tools in said space. The shield 31 hangs vertical when the door is closed.

Operating means are provided for the 25 shield 31 so that it will be automatically moved into shielding position when the door is being opened, and for this purpose the shield 31 is provided with an arm 33 extending at an angle to said shield. This arm 33 30 projects forward from the shield 31 when the shield is out of commission as in Fig. 4 and may be in the form of a loop as shown clearly in Figs. 5 and 6 and said loop projects into the path of movement of one of 35 the switch blades 22 so that when the door 9 is in the first part of its opening movement said blade will be inserted through the loop which thus becomes hooked over the blade. As the door is opened farther the contact 40 22 swings upward and carries with it the arm 33 and shield 31. The arm 33 may be made of wire so as to be more or less resilient to absorb shocks transmitted to it if the door is allowed to quickly drop open.

- 45 The door 9 is provided with a suitable handle 34 by which said door may be readily opened. Wires, not shown, will be connected to the contacts 26, 28 in a manner well understood in the art and therefore not necessary 50 to describe in detail herein.

As additional shock absorbing means the arm 15 may be attached, as shown in the drawings, to one end of a spring 35 which has its opposite end fastened to the side 55 3 or other suitable part of the case.

- When the device is in use, the parts when in the circuit-closing positions will be in the positions indicated in Figs. 2 and 4. When it is desired to open the circuit, the operator 60 will release the lock 14 and open the door 9, thus moving the contacts 21, 22 out of engagement with the contacts 26, 28 respectively so as to break the circuit. Preferably the door will be opened sufficiently far to engage the contacts 22 with the contacts 26,

thereby to hold the door securely in slanting position as in Fig. 3 so that the fuses can be readily renewed. If linemen are working on the wires, not shown, connected with the device, the operator will preferably place 70 the lock 14 through the perforations 16, 17 so as to lock the parts in circuit breaking position, thus preventing accidental or unforeseen closure of the door 9 and consequently of the circuit. 75

An important feature of the invention now becomes apparent for if any of the fuses 25 have blown out the blown out fuse may be readily removed and a new one inserted in its place in a manner well understood, 80 the construction being such that it is impossible for the operator or any one else to insert his hands or tools into the space *a* containing the contacts 28. Thus it is impossible, when the circuit breaker is open, to 85 short the circuit between the contacts 26, 28 or between the contacts 28 and the earth.

In the drawings three sets of the contacts 19, 20, 21, 22, 26, 28 and fuses 25 are shown so as to produce a three-pole circuit breaker. 90 However, it is understood that one set or any other number of sets may be employed according to the service for which the circuit breaker is to be used.

The foregoing will enable those skilled in 95 the art to which the invention appertains to make and use said invention, and it is understood that the invention is not limited to the exact embodiment shown in the drawings and herein before described but is only 100 limited within the spirit and scope of the appended claims.

We claim:

1. A circuit breaker comprising a case having a movable section and a stationary 105 portion, contacts for the stationary portion, contacts on the movable section adapted to engage the stationary contacts respectively when the movable section is in closed position, and means to hold the movable section 110 aslant when open, said means including a shield adapted to extend rearward from the movable section when the movable section is in open position.

2. A circuit breaker comprising a case 115 having a door, stationary contacts in the case, contacts on the door electrically connected to one another and adapted to engage the stationary contacts when the door is closed, and a shield in the case separate 120 from the door operative by opening of the door to position between the stationary contacts.

3. A circuit breaker comprising a case, the front of the case comprising a stationary 125 and a movable section, stationary contacts in the case, means operative by movement in one direction of the movable section to separate the space containing one of the stationary contacts from the space containing 130

the other stationary contact, and contacts mounted on the movable section to engage the stationary contacts when the movable section is moved in the opposite direction.

5. A circuit breaker comprising a case, the front of the case comprising a stationary and a movable section, stationary contacts in the case, means operative by movement in one direction of the movable section to separate the space containing one of the stationary contacts from the space containing the other stationary contact, contacts mounted on the movable section engageable with the stationary contacts respectively when the movable section is moved in the opposite direction, and means including a fuse connecting the contacts of the movable section with one another.

6. A circuit breaker comprising a case having a movable section and a stationary portion, stationary contacts in the space inside of the case, means including fuses for the movable section to close the circuit from contact to contact when the movable section is in closed position, and means operative by opening movement of the movable section to separate the space containing one of the stationary contacts from the space containing the other stationary contact.

7. A circuit breaker comprising a case having a movable section and a stationary portion, means including a stationary contact in the case and a contact on the movable section to close an electric circuit when the movable section is in closed position, and means operative by opening movement of the movable section to position between the stationary and movable contacts to obstruct access to the stationary contact.

8. A circuit breaker comprising a case having a movable section and a stationary portion, means including a stationary contact in the case and a contact and fuse on the movable section to close an electric circuit when the movable section is in closed position, and means operative by opening movement of the movable section to position between the stationary contact and fuse to obstruct access to the stationary contact.

9. A circuit breaker comprising a case having a stationary portion and a movable door, means partly on the door and partly

on the stationary portion for closing an electric circuit when the door is closed, the portion of the circuit-closing means on the door including a fuse, and a shield operative into position when the door is open to shut off a portion of the interior of the case containing one element of the stationary portion of the circuit-closing means.

10. A circuit breaker comprising a case having a door, oppositely disposed stationary contacts in the case, contacts on the door connected with one another and engageable with the first named contacts when the door is closed, a shield pivoted in the case, and means fastened to the shield and projecting into the path of movement of one of the contacts on the door to swing the shield into position to close the space containing one of the stationary contacts.

11. A circuit breaker comprising a case having its front in sections, one of said sections being stationary and the other section being hinged thereto, contacts mounted on the door and connected together, other stationary contacts in the case, one of said stationary contacts being below the level of the hinge, and a shield pivoted in the case above the level of the door hinge and operative by opening of the door to close off the space below the level of the door hinge from the space above the level of the pivot of the shield.

12. A circuit breaker comprising a case having its front in sections, one of said sections being stationary and the other section being hinged thereto, contacts mounted on the door, means including fuses connecting said contacts with one another, a shield pivoted to the back of the case and normally hanging vertically, an arm on the shield projecting forward into the path of movement of one of the contacts, and other stationary contact in the case engageable by the contacts on the door when said door is in closed position.

Signed at Los Angeles, California, this 26 day of March 1917.

DISCLAIMER.

1,253,761.—*Richard Wolfsberg and Sidney C. Smith, Los Angeles, Calif. CIRCUIT-BREAKER.* Patent dated January 15, 1918. Disclaimer filed August 2, 1919, by the assignee, *Krantz Manufacturing Company, Inc.*

Hereby enters this disclaimer—

"To the subject-matter contained in the hereinbelow-quoted claims 2, 6, and 10 so far as the Wolfsberg and Smith patent is concerned:

"2. A circuit breaker comprising a case having a door, stationary contacts in the case, contacts on the door electrically connected to one another and adapted to engage the stationary contacts when the door is closed, and a shield in the case separate from the door operative by opening of the door to position between the stationary contacts.

"6. A circuit breaker comprising a case having a movable section and a stationary portion, means including a stationary contact in the case and a contact on the movable section to close an electric circuit when the movable section is in closed position, and means operative by opening movement of the movable section to position between the stationary and movable contacts to obstruct access to the stationary contact.

"10. A circuit breaker comprising a case having its front in sections, one of said sections being stationary and the other section being hinged thereto, contacts mounted on the door and connected together, other stationary contacts in the case, one of said stationary contacts being below the level of the hinge, and a shield pivoted in the case above the level of the door hinge and operative by opening of the door to close off the space below the level of the door hinge from the space above the level of the pivot of the shield."
